UNITED STATES PATENT OFFICE.

WILLIAM H. SOMMER, OF PEORIA, ILLINOIS.

DESIGN FOR A STAY OR PICKET FOR FENCES OR GATES.

42,981.

Specification for Design.

Patented Sept. 3, 1912.

Application filed May 20, 1912. Serial No. 698,636. Term of patent 14 years.

To all whom it may concern:

Be it known that I, WILLIAM H. SOMMER, a citizen of the United States, residing at Peoria, in the county of Peoria and State of Illinois, have invented a new, original, and ornamental Design for a Stay or Picket for Fences or Gates, of which the following is a specification, reference being had to the accompanying drawing, forming a part thereof.

Figure 1 is a front elevation of the stay or picket, and Fig. 2 is an edge view of the stay or picket shown in Fig. 1.

I claim:

The ornamental design for a stay or picket for fences or gates, as shown.

WILLIAM H. SOMMER.

Witnesses:

CHAS. N. LA PORTE,
JEANNETTE M. ANDERSON.
